UNITED STATES PATENT OFFICE.

HENRY WAYMOUTH PRANCE, OF LONDON, ENGLAND.

LOUD-SPEAKING ATTACHMENT FOR TELEPHONES.

1,084,822.

Specification of Letters Patent. Patented Jan. 20, 1914.

Application filed June 25, 1913. Serial No. 775,698.

To all whom it may concern:
Be it known that I, HENRY WAYMOUTH PRANCE, consulting motor engineer, residing at London, England, have invented certain new and useful Improvements in Loud-Speaking Attachments for Telephones; and I do hereby declare the following to be a full, clear, and exact description of the invention, such as will enable others skilled 10 in the art to which it appertains to make and use the same.

This invention relates to instruments for use in connection with telephone receivers and has for its object the magnification 15 of the sound reproduced by the receiver so that the voice of the person speaking at the farther end of a telephone line can be heard at the receiving end without the receiving instrument being held to the receiver's ear. The invention thus obviates the necessity of remaining by the instrument when waiting for a message to be continued.

It is carried out as follows:—A sound 25 trumpet of suitable shape and size is placed in front on a platform or support provided with guides disposed behind said trumpet. Said guides are adapted to support the telephone receiver in such a manner that when 30 same is placed in position the ear piece presses against the small end of the sound trumpet; the diaphragm of the receiver being coincident with the orifice of the small end of the trumpet. The sound from the 35 receiver is thus magnified and may be heard throughout a room of usual size.

In a modified form the sound trumpet is made approximately U shape, and the smaller end is provided with a horizontal 40 tray shaped to correspond to the ear piece of the receiver, upon which the telephone receiver is supported when the device is in use. At the termination of the conversation the receiver is lifted off the device and re- 45 placed upon the telephone instrument.

The invention will now be described more particularly with reference to the accompanying drawings in which:

Figure 1. is a side view of the invention.

Fig. 2. is a front view of one of the supporting guides, and Fig. 3. shows a modified form of the invention. 50

In the drawings, 1 is the sound trumpet made from any suitable material, and attached to the platform or support 2, by 55 means of the brace 3 or otherwise. Behind said trumpet are mounted the guides 4 and 5. The guide 4 is made bow shaped as shown, while the guide 5 is slightly inclined. When in use, the telephone receiver 6 is 60 placed on the guide 4, when, on account of the inclined position of guide 5, said receiver slides into position against the trumpet 1, and with the ear piece pressing against the small end 7 of the same. 65

In the modified form shown in Fig. 3, the trumpet 1 is made approximately U shaped, the small end 7 being provided with a horizontal tray 8 shaped to correspond to the ear piece of the receiver, adapted to support 70 the receiver 6 in such a manner that the diaphragm of same is coincident with the trumpet orifice. If desired means may be provided for depressing the receiver hook of the telephone when the invention is not 75 in use. The two forms illustrated are given by way of example.

I claim:—

The combination, with a supporting base, and a trumpet secured thereto and having 80 its main portion arranged horizontally; of an inclined guide secured to the base plate to the rear of the inlet opening of the trumpet and adapted to press the front end of a telephone receiver against the trumpet, 85 a support secured to the base between the trumpet and the guide, and a telephone receiver supported horizontally and held in line with the inlet opening of the trumpet by the said support and guide. 90

In testimony whereof I affix my signature, in presence of two witnesses.

HENRY WAYMOUTH PRANCE.
